ILLUMINATING APPARATUS

Filed June 15, 1929

UNITED STATES PATENT OFFICE

GEORGE H. CUSHING, OF WASHINGTON, DISTRICT OF COLUMBIA

ILLUMINATING APPARATUS

Application filed June 15, 1929. Serial No. 371,258.

This application is a continuation in part of application Serial No. 752,214, filed November 25, 1924.

This invention relates in general to illumination and more particularly has reference to household lamps employing the principle of secondary reflection, or indirect illumination, for spreading light emanating from a source, over an area to be illuminated.

10 A major object of the present invention is to provide an illuminating structure in which direct rays emanating from a source of light are shielded so that the light source can never be directly observed.

15 Another object of this invention is to provide an illuminating device which utilizes all, or substantially all, of the light emanating from the light source, and one that is adapted to spread the light so as to evenly distribute it over an area to be illuminated.

20 Yet another object of this invention is to provide a table or reading lamp which so controls the light that light ordinarily permitted to be wasted is intercepted and directed to the location to be illuminated.

25 Still another object of this invention is to provide a lamp, the light from which simulates daylight, and has characteristics making it particularly desirable for use in examining textile materials and for matching colors.

30 A still further object of this invention is to provide a compact lamp, which is strong and sturdy in construction, which is formed of easily obtainable parts, requiring no adjustments, and which are readily accessible for cleaning and inspection.

With these and other objects in view, which may be incident to my improvements, 35 the invention consists in the parts and combinations to be hereinafter set forth and claimed, with the understanding that the several necessary elements comprising my invention may be varied in construction, proportions and arrangement, without departing from the spirit and scope of the appended claim.

The present invention resides in the concept of applying the principles of secondary reflection, or indirect illumination, to house-

hold lighting, and particularly to lamp structures such as table lamps and similar devices.

In carrying out my invention an illuminating structure is provided having a base in which is incorporated a light source. A primary reflector is positioned about the light source in such a manner as to redirect rays of light emanating from the source upwardly. The base is provided with a super-structure adapted to support a secondary reflector in a definite position relative to the primary reflector, and above the base. This secondary reflector is so constructed as to redirect the light impinging thereon to a definite area about the base of the lamp.

In order to make my invention more clearly understood, I have shown in the accompanying drawings means for carrying the same into practical effect, without limiting the improvements in their useful applications to the particular constructions, which, for the purpose of explanation, have been made the subject of illustration.

In the drawings:

Figure 1 is a side elevation of a household lamp constructed in accordance with the present invention.

Figure 2 is a vertical sectional view of the lamp depicted in Figure 1 taken on line 2—2 thereof and showing the construction and arrangement of the primary and secondary reflectors.

Figure 3 is an enlarged sectional view taken on line 3—3 of Figure 2 showing the plated construction of the reflecting surfaces.

Figure 4 is a detailed view showing a modified bracket construction.

Figure 5 is a partial plan view of the reflecting surface of the secondary reflector associated with the lamp forming the subject matter of the invention.

Referring to the drawings, in which similar reference characters indicate similar parts throughout the several views of the drawings, there is shown in Figure 1 a household lamp having a pedestal-like base 1, which is in the form of a hollow member 2 shaped as desired. Base 1 is provided with a foot portion 3, in which is incorporated a block 4, which serves to strengthen the foot portion 70

and retains the same in its initial shape. If desired, the block 4 may be constructed of material of relatively high density, in which instance it will be difficult to turn the lamp over.

The block 4 may be provided with a central opening 5, and a radial passageway 6, the latter registering with an opening in the foot 3 of the lamp, through which a suitable cord 10 7 passes. A bushing 8 may be inserted in the passageway to insure alignment of the duct 6 and the opening in the foot 3. A pad 9, constructed of felt or any other suitable material, is attached to the bottom of the base structure to prevent the structure from marring finished surfaces on which it may be placed.

The upper end of the hollow body 2 is spun or shaped in any suitable manner to provide a shoulder 10 and a flange 11, which serve to support other structure. A primary reflector 12, preferably of the parabolic type, is mounted within the hollow base 2. While this reflector is described as parabolic, I wish it to be clearly understood that it may be of a form other than truly parabolic. For instance, this reflecting surface may be similar to that generated by gyrating a parabola with its axis arranged at any desired angle, or it may be of any other suitable form. In any event the focal length may be of any predetermined value. The particular shape of the reflector 12 will, of course, depend on the manner in which the light is to be reflected therefrom. This reflector is provided with a peripheral flange 13 adapted to cooperate with flange 11 to position the reflector in the base 2.

Reflector 12 is provided with a central opening in which is secured a socket 14, which receives the base of an electric light bulb 15, and a plug 16 connected with the current supply cable 7. Light emanating from the filament in bulb 15 will impinge on the surface of the reflector 12, and will be directed in a direction depending upon the particular shape of the reflector.

A band 17 is fitted on the shoulder 10 and has attached thereto a plurality of supporting arms, or brackets 18. These brackets support a superstructure with which is associated a secondary reflector 19. The ends of the arms, or brackets, 18 are received between the reflector 19 and the flange formed by turning in the edge 21 of the cover 20. A split resilient ring 27 is fitted between the reflector 22 and the arms 21 so that all parts are held in an assembled relation. If desired, however, the brackets 18 may be associated with the superstructure, as shown in Figure 4, that is, by shaping the brackets 18 to receive the cover member 20 and the reflector carried thereby. This secondary reflector has a surface similar to that generated by revolving a curve corresponding to that

of a semi-cubic parabola of the general formula of $y^2 = ax^3$, about its "x" axis. The particular curvature of the reflector, of course, depends upon the light distribution to be effected.

While upon a casual observation, the reflecting surface of reflector 19 appears smooth, it is in reality formed of a multiplicity of segregated flat sections arranged in stepped relation. This arrangement comprises a series of flat planes blended at their intersections, each flat assuming a different angular relation to the true horizontal, but so pitched that the light projected by no two such flats will fall upon the same point. It has been found that this construction of the secondary reflector produces far better results than are obtained by constructing a reflector having an actually continuous surface.

A reflector of the general shape above described is fitted into a cover member 20, the edge 21 of which is spun or otherwise shaped to retain the reflector 19 in position. Cover member 20 may be provided with a knob 22 or other structure, by means of which the lamp may be moved, and which serves to ornament the structure.

The arms 18 may be secured to the cover 20 in any desired manner, and the band 17 and the reflector 12 may be fixed to the base 2 by means of a ring member 23, which may be secured to the base 2.

The reflectors 12 and 20 may be formed of a plated metal, or of metal on which is plated a plurality of other metals. I have found that reflecting surfaces which are plated first with gold and then with silver are especially desirable. Figure 3 shows a section of one of the reflectors; the base metal of which the reflector is constructed is indicated by reference numeral 24. Plated on the base metal is a layer of gold 25, and superimposed on the layer of gold is a layer of silver 26. It has been found that the reflection characteristics of reflectors plated as described are better than in the case of reflectors plated solely with a lustrous metal, such as silver. Also, reflectors constructed as described are instrumental in affecting the light reflected therefrom to make it similar to daylight. Light from reflectors constructed as just described is particularly advantageous for examining materials and for comparing and matching colors.

If desired, the reflectors may be formed of glass, or other suitable transparent material which is backed by light reflecting substances such as used in preparing ordinary mirrors.

The concept of the present invention may be embodied in various types of lamps, such as table lamps, desk lamps, counter lamps, floor lamps, ceiling lamps and lamps of various other types adapted to be used for all purposes. Lamps constructed in accordance with

the present invention are particularly desirable as reading lamps, since the light is soft, approaching that of natural daylight, and under no circumstances can a person in the 5 vicinity of the lamp observe any glare, such as could be seen by directly viewing the light source.

It will be appreciated that the structure shown in the drawings is more or less dia-
10 grammatic, and that the precise details of construction of the essential portions of the lamp will be determined by the particular use for which the lamp is to be employed.

While I have shown and described the pre-
15 ferred embodiment of my invention, I wish it to be understood that I do not confine myself to the precise details of construction herein set forth, by way of illustration, as it is apparent that many changes and variations
20 may be made therein by those skilled in the art, without departing from the spirit of the invention or exceeding the scope of the ap-
pended claim.

I claim:

25 A household lamp comprising a hollow base member, a foot portion therefor, a deep para-
bolic primary reflector positioned within the base member, the mouth of said reflector be-
ing supported upon the upper end of said
30 base member, a light source positioned at the apex of said primary reflector, a plurality of arms extending upwardly from the upper end of the base member, an annular opaque
35 parabolic secondary reflector having a re-
flecting surface formed of a plurality of seg-
regated flats and an opaque cover member for
40 said secondary reflector both supported by
said arms, said secondary reflector being so
positioned with respect to the primary re-
flector as to intercept and redirect all of the
45 light reflected thereby and also all of the un-
reflected light emanating from said light
source.

In testimony whereof I affix my signature.

45 GEORGE H. CUSHING.
